Patented Jan. 4, 1921.

UNITED STATES PATENT OFFICE.

JOHN C. DAYNIX, OF PHILADELPHIA, PENNSYLVANIA.

HYDROKINETIC MECHANISM.

1,364,617.

Specification of Letters Patent.

Patented Jan. 4, 1921.

Application filed April 5, 1920. Serial No. 371,230.

To all whom it may concern:

Be it known that I, JOHN C. DAYNIX, a citizen of the United States, residing at Philadelphia, in the county of Philadelphia and State of Pennsylvania, have invented a certain new and useful Improvement in Hydrokinetic Mechanism, whereof the following is a specification, reference being had to the accompanying drawing.

10 My invention relates to engines of the hydraulic ram class. It is the usual practice to continuously supply water to such a ram with the effect that the ram is intermittently operated to raise a very small portion of the 15 water thus supplied but all of the water supplied to it during each interval in which the moving parts of the ram are returning to their initial positions for another impulse is wasted. It is the object of my invention to 20 intermittently supply such an impulse engine or group of engines with water; the intermissions of the supply being so timed as to correspond with the intervals of operation of such engine; so as to minimize the 25 amount of water wasted; the effect of my invention being to supply water to such an engine only when it is ready to receive it and to withhold the water supply during such intervals as are required for the parts of the 30 mechanism to resume their initial position to receive the next charge of water, and to render the gravitational acceleration of the separate charges of water effective in the operation of said engine.

35 As hereinafter described, my invention includes automatically intermittently operative water charging mechanism capable of receiving, measuring and intermittently dispensing charges of water of predetermined 40 volume and at predetermined intervals, from the body of water to be supplied to the apparatus to which it is to be supplied. In the form of my invention hereinafter described, such charging mechanism includes a tilttable 45 measuring and dispensing trap normally presented in position to receive water from said supply but arranged to automatically tilt from that position when it has received a predetermined quantity of water and, by its 50 tilting movement, shut off communication with the supply, and dispense, to the ram

mechanism, the charge of water which has been received by said trap; said trap having means to adjustably vary its operation both as to the volume of water received for each 55 charge and as to the intervals of time between its tilting movements; so that such charging mechanism may be calibrated in accordance with the requirement of the ram mechanism it supplies.

60 My invention includes the various novel features of construction and arrangement hereinafter more definitely specified.

In said drawing; Figure I is a vertical sectional view of an apparatus embodying 65 my invention; parts thereof being shown in elevation.

Fig. II is a fragmentary plan sectional view of said apparatus, taken on the line 70 II, II in Fig. I.

Fig. III is a vertical sectional view of one of the check valves through which water is received by the rams shown in Figs. I and II.

Fig. IV is a vertical sectional view of the 75 water inlet valve of the tilttable trap shown in Figs. I and II; in the open position shown in Fig. I.

Fig. V is a sectional view of the valve shown in Fig. IV, but with the valve turned 80 to closed position, corresponding with the position of said trap shown in dotted lines in Fig. I.

I find it convenient to mount my improved mechanism in a tank 1, indicated in 85 Figs. I and II, which may be conveniently formed of reinforced concrete, extending below the level of the body of water 2 from which the apparatus is to be supplied. Water is admitted from said supply 2 90 through the perforated screens 3 to the inlet conduits 4 which are controlled by the valves 5 and connected with the valve tube 6. Said valve tube 6 is held stationary and provided with a circumferential series of 95 three ports 7 adapted to register with the ports 8 in the valve casing 9, as indicated in Figs. I, IV, and V. Said valve casing is a fixture in the tilttable trap 11 which is thus pivotally supported upon said stationary 100 valve tube 6 and contains the chamber 12 in which the charge of water 14 is received.

- Said trap 11 is so proportioned that when empty it gravitates to the position shown in full lines in Fig. I, but, when fully charged with water, gravitates to the position shown in dotted lines in said figure and is conveniently provided with the counterbalance 16 which may be adjusted by turning it on the screw shaft 17 which is mounted upon the bottom of said trap 11, 5 in rigid relation therewith, so that the quantity of water 14 necessary to overbalance said trap to the position shown in dotted lines in Fig. I may be variably predetermined by the adjustment of said counterbalance 16. Said trap 11 has the discharge outlet 18 which is normally closed by the flap valve 19, in the position shown in Fig. I. Said valve 19 is pivoted at 20 upon the valve lever 21 which is fulcrumed at 22 10 upon said trap 11 and depends in operative relation with the roller 23 which is pressed into engagement therewith by the spring 24 in the stationary housing 25, by pressure of said spring upon the collar 26 on the plunger 27 which carries said roller and is mounted to reciprocate in said housing 25. Said housing 25 is conveniently fixed upon the hopper 30 which may be supported beneath the discharge end of said tiltable trap 15 25 30 35 40 45 50 55 60 65 70 75 80 85 90 95 100 105 110 115 120 125 shown in dotted lines in said figure, thus automatically closing the inlet ports 7 and opening the outlet port 18 of said trap 11 and discharging that water charge down-
 5 wardly through the conduit 34 into the engine base 36. Said conduit 34 is so proportioned both in diameter and length that the water thus transmitted therethrough attains the desired velocity when it reaches the inlet
 10 valves 50 of the respective engines so as to open the latter and pass into the respective domes 43 in opposition to the pressure of the air which is compressed therein. During the interval of time while the puppets
 15 52 of said valves 50 are resuming their initial closed position shown in Fig. III, and the water is being driven from said domes 43 through said ports 55 and check valves 58 of the respective engines; said tank 11
 20 automatically returns to its initial position, shown in full lines in Fig. I, because when thus emptied, it is overbalanced by the weight 16 and therefore gravitates to the position shown in full lines in Fig. I, thus
 25 again opening its inlet ports 7; so that, by the time equilibrium is restored in said engine domes 43, another water charge 14 is delivered thereto.

I find it convenient to provide said trap 11
 30 with the air vent cock 60 and to also provide said base 36 with the air vent cock 61 to permit the operator to manually release any surplus of compressed air thereat.

The operation above described does not
 35 cause said engine to raise all of the water of each charge 14 and the surplus is permitted to escape from said base 36 through the drain pipe 62, under control of the valve 63, to the drain tank 65 from which it may be
 40 continuously or intermittently withdrawn.

Although I have shown a group of five hydrokinetic engines, it is obvious that my invention may be embodied in mechanism including any desired number of units and,
 45 of course, may be embodied in mechanism including but a single ram. Moreover, it is obvious that said charging mechanism may be otherwise constructed and arranged.

Therefore, I do not desire to limit myself
 50 to the precise details of construction and arrangement herein set forth, as various modifications may be made therein without departing from the essential features of my invention, as defined in the appended claims.

55 I claim:

1. The combination with a hydrokinetic engine, of an intermittently operative ram type; of mechanism constructed and arranged to intermittently supply water to
 60 said engine at intervals similar to the intervals of operation of said engine, including a tilttable trap having a water inlet and a water outlet, and means operative to alternately open and close said inlet and outlet;

whereby water is supplied to said engine 65 only when it is in condition to receive it and withheld during such intervals as are required for the moving parts of the engine to assume their initial position to receive a charge of water. 70

2. The combination with a hydrokinetic engine, of an intermittently operative ram type; of mechanism constructed and arranged to intermittently supply water to said engine at intervals similar to the intervals of operation of said engine, including a tilttable trap having a water inlet and a water outlet, and means operative to alternately open and close said inlet and outlet, by the movement of said trap; whereby, water 80 is supplied to said engine only when it is in condition to receive it and withheld during such intervals as are required for the moving parts of the engine to assume their initial position to receive a charge of water. 85

3. The combination with a hydrokinetic engine, of an intermittently operative ram type; of mechanism constructed and arranged to intermittently supply water to said engine at intervals similar to the intervals of operation of said engine, including a tilttable trap having a water inlet and a water outlet, and means operative to alternately open and close said inlet and outlet, by the movement of said trap; said trap being above the water inlet of said engine and having an inclined conduit connecting it therewith; whereby, water is supplied to said engine only when it is in condition to receive it and withheld during such intervals 100 as are required for the moving parts of the engine to assume their initial position to receive a charge of water.

4. The combination with a group of hydrokinetic engines of the intermittently operative ram type, of different sizes; of a base common to said engine and having a water inlet and outlets to the respective engines; the smallest engine being nearest said inlet; of mechanism constructed and arranged to intermittently supply water to the inlet of said base at intervals similar to the intervals of operation of said engines; whereby, water is supplied to each engine only when it is in condition to receive it 115 and withheld during such intervals as are required for the moving parts of the engine to assume their initial position to receive a charge of water.

5. The combination with a hydrokinetic engine, of an intermittently operative ram type; of mechanism, independent of said engine, constructed and arranged to intermittently supply water to said engine at intervals similar to the intervals of operation 125 of said engine; whereby, water is supplied to said engine only when it is in condition to receive it and withheld during such in-

tervals as are required for the moving parts of the engine to assume their initial position to receive a charge of water.

6. The combination with a hydrokinetic engine, of an intermittently operative ram type; of mechanism, independent of said engine, constructed and arranged to intermittently supply water to said engine in separate charges and including means arranged to so direct said charges to the ad-

mission valve of said engine as to render the gravitational acceleration of said charges effective in the operation of said engine.

In testimony whereof, I have hereunto signed my name at Philadelphia, Pennsylvania, this twenty-ninth day of March, 1920.

JOHN C. DAYNIX.
